UNITED STATES PATENT OFFICE.

WILLIAM C. JACOBS, OF PALESTINE, ILLINOIS, ASSIGNOR OF ONE-THIRD TO VIVIAN CARTER, OF PALESTINE, ILLINOIS.

STEAM-DRYING SYSTEM FOR LOCOMOTIVE-BOILERS.

1,196,783.

Specification of Letters Patent.

Patented Sept. 5, 1916.

Application filed March 13, 1916. Serial No. 83,921.

To all whom it may concern:

Be it known that I, WILLIAM C. JACOBS, a citizen of the United States, residing at Palestine, in the county of Crawford and State of Illinois, have invented certain new and useful Improvements in Steam-Drying Systems for Locomotive-Boilers, of which the following is a specification.

The chief purpose of this invention is to provide the engines of locomotives with superheated steam that will not only be superheated but heated to a point such that it will be thoroughly dried.

The invention also contemplates such early and thorough heating of the steam that there will be an immediate supply when the locomotive starts out on a trip instead of requiring several miles of travel under forced draft before the drying of the steam becomes effective.

Another object of the invention is the provision of a boiler so designed that the superheating unit may be added without materially increasing the length of boilers now manufactured.

Other objects and purposes of the invention will appear in the disclosure thereof and to that end be it said the invention consists in the structure of parts and in their combination and association substantially as hereinafter set forth and claimed.

The accompanying drawings form a part of this specification and in them Figure 1 is a vertical longitudinal medial section through a locomotive boiler embodying this invention. Fig. 2 is a vertical transverse section through the fire box portion taken on the line 2—2 in Fig. 1. Fig. 3 is a like section through the barrel of the boiler seen in Fig. 1 taken on the line 3—3. Fig. 4 is an elevation of the baffle sheet in the superheater of the drying system shown in Fig. 1. Fig. 5 is a vertical longitudinal medial section of an ordinary locomotive boiler modified for the addition of the superheater of this invention. Fig. 6 is a vertical transverse section through the barrel of the boiler in Fig. 5 taken in line 6—6. Fig. 7 is an elevation of the baffle sheet in the superheater shown in Fig. 5.

In the first four figures of the drawings 10 indicates the fire box with its arch 11 and door opening 12; while 13 indicates the

barrel, 14 the forward smoke box with its door 15, exhaust steam nozzle 16, spark-arresting screen 17 and series of petticoats 18 in line with the stack 19; and 20 indicates the steam dome from which leads the steam pipe 21 to the superheater 22 with its steam dome 23, throttle box 24 and steam pipe 25 which conveys the superheated dry steam to the engines of the locomotive, not shown. The superheater 22 is located in the forward end of the barrel and to give it that space the flues 26 leading directly from the fire box 27 are shortened, the forward flue sheet of the boiler being indicated at 28.

The heads of the superheater are indicated by 28 and 29 and located between and parallel thereto is a baffle sheet 30 which extends down about five sixths of the way from the top toward the bottom. In said heads the flues 31 are tightly secured in the usual manner but are simply passed through holes in the baffle sheet with a snug fit. They are preferably located in alignment with the boiler flues. The steam pipe 21 enters to the rear of the baffle sheet and the steam dome 20 is located forward of said sheet.

To make up for the reduced heating surface due to shortening the flues 26 the crown sheet 32 is somewhat lowered and flues 33 are located above it extending from the forward sheet 27 to the rear sheet 34. Still more flues as indicated at 35 are added above the flues 33 to assist in heating and drying the steam. Radial stays 36 from crown sheet to boiler shell pass between the flues 33 and 35. A rear smoke box 37 is provided and has the usual doors opening into it the hinges of which are represented at 38.

Other features of the structure and system will appear in the description of the routes of steam and products of combustion or gases. The gases from the fire box pass forward through flues 26 across the compartment 39, between forward flue sheet 27 and the superheater, then through flues 31 of the superheater to baffle sheet 40 which directs them around baffle plate 41 rearward through flues of the superheater across compartment 39 between arched bridges 42 and 43 thence through flues 33 into smoke box 37 whence on rounding baffle plate 44 they pass forward through flues 35 the upper part

of compartment 39 and through the upper flues of the superheater then downwardly between baffle sheets 40 and 45 to the lower part of the smoke box whence they arise 5 through the spark screens 17 and petticoats 18 to escape through the stack 19.

The steam arising from the water, whose surface is about ten or twelve inches above the crown sheet, will pass between the uppermost flues 33 and the flues 35, which will begin the heating thereof, thence to steam dome 20 and through pipe 21 to superheater 22 down among the flues 31 thereof around baffle sheet 30 and up among the flues 31 to 15 the steam dome 23 to throttle box 24 thoroughly dried. From there it passes to the engines at the will of the engineer.

In the compartment 39 a deflector 46 is located over flues 26 and is so mounted as 20 to serve as an adjustable draft-regulating baffle sheet. The bridges 42 and 43 in said compartment are located as seen in Fig. 3 between rows of flues and separate the respective banks 26, 33 and 35 from one another. They are preferably of any suitable 25 refractory material and may be held in place by channel or T-irons on the flue sheets 27 and 28. Said compartment is large enough to admit a workman and is provided 30 with a suitable manhole typified at 47. In the baffle sheet 40 in the forward smoke box is located a direct-draft damper 48. The usual cinder hopper is located at 49 in the forward smoke box and a like hopper 50 is 35 provided for compartment 39.

Instead of the usual petticoat pipe shown at 51 in Fig. 5 a number of petticoats 18 are shown in series in the preferred form of drying system depicted in Fig. 1. This series 40 of petticoats, spaced apart axially, provides a number of lateral intakes for leading the gases from the smoke box to the stack in response to the forced draft induced by the 45 exhaust from nozzle 16. Thereby a greater degree of suction is exerted on the gases as they traverse the triple path from the fire box to the stack.

The system outlined provides for early 50 effective drying of the steam and for raising it to the maximum degree of heat. If at times the steam should prove too hot it may be cooled or reduced in temperature by means of a valved bypass for cutting out the superheater 22. Such a bypass is typified in Fig. 1 in dotted lines at 52 with its lever-stemmed valve 53.

The drying system simplified and applied 60 to the standard locomotive boiler is illustrated in Figs. 5 to 7. Therein the flues 26 have been shortened and the forward flue sheet 27 moved back sufficiently to allow the insertion of the superheater 54 which slightly varies from superheater 22 in not 65 having flues through its upper part, the flues thereof terminating at the level of those of

the boiler, and stay rods 55 being substituted for the flues removed or omitted. In this form also the inclosed steam pipe 56 passes through compartment 39 in a downward direction and enters the first chamber 70 of the superheater just above the flues thereof. A draft-regulating baffle 57 is also provided in the compartment 39, its position being controlled by means of a crank arm 58. A like crank arm 59 is also provided 75 for controlling the position of the draft-regulating sheet 46 in Fig. 1 and another 60 is provided for controlling the damper 48 in baffle sheet 40. These several crank arms are connected with the cab by operating rods 30 when the boiler is mounted. The superheater in both locations is preferably provided with an automatic water trap depicted at 61 for drawing off water of condensation. In the latter adaptation of the 35 drying system the steam passes from dome 20 through pipe 56, which traverses compartment 39, into the superheater 54 then down to the bottom thereof, around baffle sheet 62 and up to dome 23 and throttle box 90 24 whence its passage to the engines is controlled by the engineer.

While this invention has been described with reference to a locomotive boiler it must be understood that it is not limited to that 95 adaptation since it may be incorporated with any other style of steam boiler.

The invention claimed is—

1. The combination with a boiler, of a superheater having flues parallel with the 100 boiler flues and located transversely of the barrel of the boiler in advance of the forward flue sheet and leaving a compartment between it and said flue sheet, partitions extending across said compartment for the 105 purpose set forth, a regulable hinged baffle sheet in the lower part of said compartment, a baffle sheet forward of said superheater for returning the gases from the fire box toward the rear of the boiler, and a 110 direct-draft damper in said baffle sheet.

2. The combination with a boiler, of a superheater having flues parallel with the 115 boiler flues and located transversely of the barrel of the boiler in advance of the forward flue sheet and leaving a compartment between it and said flue sheet, a hinged draft-regulating baffle sheet in said compartment and means for swinging said baffle sheet.

3. In a steam drying system for locomotive boilers the combination with the fire box and forward smoke box, of a superheater having longitudinally extending flues and located across the barrel of the boiler 125 between said smoke box and the forward flue sheet of the boiler and having an intermediate depending baffle sheet with steam inlet at one side and outlet at the other, a set of boiler flues extending from the fire box to 130

the forward flue sheet, a set of flues above the crown sheet extending through the water space from the rear flue sheet to the forward flue sheet, another set of flues extending through the steam space from said rear sheet to said forward sheet, a smoke box at the rear flue sheet for said last two sets of flues, and means for directing the gases from the fire box successively through said three sets of boiler flues and thrice through the 10 superheater.

In testimony whereof I have affixed my signature.

WILLIAM C. JACOBS.
